UNITED STATES PATENT OFFICE.

FRED E. GROSVOLD, OF EAU CLAIRE, WISCONSIN.

FLOOR-DRAIN.

1,301,687.

Specification of Letters Patent. Patented Apr. 22, 1919.

Application filed August 3, 1918. Serial No. 248,194.

To all whom it may concern:

Be it known that I, FRED E. GROSVOLD, a citizen of the United States, and a resident of Eau Claire, in the county of Eau Claire 5 and State of Wisconsin, have invented a new and Improved Floor-Drain, of which the following is a description.

My invention although capable of wider application is more particularly intended for 10 use in connection with a combination floor drain and trap, in which the clean-out pipe is disposed transversely of the drain for communicating therewith.

An important object of the invention is to 15 provide on the plug of the clean-out pipe a member having a limited guided movement relatively to the clean-out pipe, whereby to limit the opening movement of the plug and thereby, in preventing its complete withdrawal, avoiding the misplacing or loss of 20 the plug.

A further object of the invention is to dispose the plug when open in a position to 25 prevent the closing of the cover until the plug is restored to the clean-out pipe, whereby the latter will not be thus accidentally left open for the escape of sewer gas.

Reference is to be had to the accompanying drawings forming a part of this specification, 30 it being understood that the drawings are merely illustrative of one example of the invention.

Figure 1 is a longitudinal vertical section of a drain and trap equipped with my invention, showing the clean-out plug open 35 affording access to the clean-out pipe and at the same time obstructing the closing of the drain cover;

Fig. 2 is a similar view with the plug in 40 position closing the clean-out pipe and with the drain cover in the closed position;

Fig. 3 is a partly sectional plan view.

The drain designated generally by the numeral 10 may be of any approved form having 45 a trap 11 leading to the soil pipe 12, the drain having a clean-out pipe 13 above the trap for affording access to the pipe 12, said parts being generally known. The numeral 14 indicates the perforated cover of the 50 drain and will be hereinafter particularly referred to.

The clean-out plug 15 is adapted to be screwed into the end of the clean-out pipe 13 at the flaring mouth of the drain beneath the 55 cover. In order to prevent the complete withdrawal of the plug the latter is equipped

with a retainer 16, here shown as U-shaped or of yoke form, the cross bar of which is swiveled to the plug 15 by a bolt 17 extending axially through said plug. Thus, the 60 plug may turn relatively to the retainer 16 in inserting and removing the plug. Said retainer has side arms 18 passing through fixed keepers 19 on the clean-out pipe 13 at the interior, whereby as the plug is inserted 65 or removed the arms 18 will have guided sliding movement in said keepers. The arrangement of the arms 18 and keepers 19 is such that when the free ends of the arms are brought adjacent to the keepers the arms 70 will engage the keepers to prevent complete withdrawal of the plug 15 from the drain, the arrangement in the given example consisting of a notch 20 in each arm 18 whereby the arms will drop into engagement with 75 the keepers. Thus, if it should be attempted to remove the plug through the top of the drain after removing the cover 14, then the removal must be done deliberately because the tendency of the arms 18 will be to engage 80 their notched portions 20 with the keepers 19. The plug 15, however, with the arms 18 still engaging the keepers may be permitted to lie in the flaring portion of the drain as shown in Fig. 1, leaving ample clearance for 85 the insertion of a clean-out wire or other tool in the pipe 13. Thus, the accidental loss or displacement of the plug will be prevented.

I utilize the retainer plug to prevent the closing of the cover 14 by obstructing the 90 closing movement thereof, for which purpose in the illustrated example a depending lug 21 is formed on or secured to the cover at the under side in a position to rest on the arms 18 or one of them, when the plug is in the 95 open position as shown in Fig. 1. The cover at the opposite end from the lug 21 has a lateral lug 22 engaging a mating notch 23 in the drain. Thus, the arrangement is such that the opening movement of the plug will 100 carry the arms 18 in a path across the drain and beneath the cover to form an obstruction to the latter.

I would state in conclusion that while the illustrated example constitutes a practical 105 embodiment of my invention, I do not limit myself strictly to the mechanical details herein illustrated, since manifestly the same can be considerably varied without departure from the spirit of the invention as 110 defined in the appended claims.

Having thus described my invention, I

claim as new, and desire to secure by Letters Patent:

1. A drain including a clean-out pipe extending laterally from the drain, a cover for said drain, a plug for said pipe, and a member on said plug and movable therewith, in the opening of the plug, in a transverse path below the cover to a position to obstruct the closing of said cover until the plug is replaced in the clean-out pipe.
2. A drain including a lateral clean-out pipe, a plug for said pipe, means to limit the movement of the plug away from said pipe to thus position the plug in the drain, a cover for said drain, and coacting means on

the cover and plug to cause the plug to obstruct the closing of the cover until the plug is in position in the clean-out pipe.

3. A drain including a clean-out pipe, a plug therefor, and an extension member on said plug having limited movement relatively to the clean-out pipe, to prevent complete withdrawal of the plug from the pipe to thereby position the plug in the drain beneath the position of the cover, said cover having a depending member to be engaged by said extension when the said plug is withdrawn from the clean-out pipe.

FRED E. GROSVOLD.
